UNITED STATES PATENT OFFICE.

HENRI ARMAGNAT AND PIERRE FRELY, OF PARIS, FRANCE.

ELECTRIC REPRODUCER FOR PHONOGRAFS.

1,384,295.

Specification of Letters Patent. Patented July 12, 1921.

Application filed May 19, 1919. Serial No. 298,185.

To all whom it may concern:

Be it known that we, HENRI ARMAGNAT and PIERRE FRELY, residing at Paris, France, have invented new and useful Improvements in or Relating to Electric Reproducers for Phonographs, for which we have filed an application in France, May 17, 1918, of which the following is a specification.

This invention relates to improvements in talking machines and consists primarily in an element which is called an electrical transmitter and which comprises a vibrating blade placed between the north and south poles of a magnet and determining, by its vibration, variations in the induction of a coil whereby in the coil a pulsating or alternating current is set up, the apparatus being adapted to be placed upon the arm of the talking machine and the vibrations of the blade being due to the oscillation of this arm under the influence of the needle or style which follows the curve of the sound groove. The pulsating or alternating current which is set up takes the place of the acoustic vibration ordinarily produced in talking machines and this pulsating or alternating current is employed to produce acoustic vibrations in telephone receivers, sound amplifiers, or loud speaking receivers and the like.

In the accompanying drawing:

Figure 1 is a vertical view of the magnetic transmitter;

Fig. 2 is a horizontal section along A—B of Fig. 1;

Figs. 3 and 4 are respectively an elevation-view and a plane-view showing a reproducer in combination with a phonographic disk.

A soft-steel blade 1 is fixed at its lower part in a bracket 2 clamped on the arm 3 of the reproducer. At its upper part it is fixed in a bracket 4 which is connected to the magnet 5 by screws 6. By means of these screws, the blade 1 is adjusted in such a manner as to be equally distant from the poles N and S.

A frame 7 executed in a non-magnetic metal surrounds the legs of the magnet 5 and is provided with a screw 8 which enables the adjustment of the distance between the poles N and S.

A coil 9 surrounds the blade 1 without touching it.

The arm 3 oscillates in a horizontal plane according to the movements transmitted by the style 10 (Figs. 3 and 4).

which follows the waves of the line traced on the disk 11.

Owing to its inertia, the magnet cannot follow the oscillations and the blade 1 comes alternately nearer to each one of the poles N and S.

At rest, when everything is properly adjusted, the blade 1 being in the neutral plane of the magnet is not magnetized, but as soon as it deviates from this axis, it is magnetized in proportion with the relative displacement; consequently owing to the oscillation of the arm 3, the magnetic flux varies in the blade 1 and an electromotive force is generated in the spool 9.

The electromagnetic apparatus hereinbefore described may be located at a variable distance from the style 10. If it is directly above this style, the greatest sensibility is obtained but notable efforts are excited on the style 10 and consequently the wear and the alteration of the disk are increased. Of course, the sensibility decreases when the distance d (Fig. 3) from the axis of the blade to the style comes nearer to r the radius of the arm.

Experience shows that a good proportion is:

$$d = \frac{3}{4} r.$$

85

It is very important that the electromagnetic device has a perfect static and dynamic balance relatively to the blade 1, in such a manner as to avoid any perturbing noises resulting from the friction of the style in its furrow. In fact, this friction produces vertical vibrations of the style. These vibrations do not move the blade 1 relatively to the poles N and S when the device is properly balanced, but they modify the relative position of the blade in respect of the poles when the symmetry is not perfect.

Owing to the elasticity of the blade 1 which connects it to the arm 3, the magnet forms an oscillating system, the period of which must be greater than the period of the oscillations which are to be reproduced.

At the extremity opposed to the style 10, the arm 3 (Figs. 3 and 4) is provided with a double joint in such a manner as to follow without notable resistance the movements of the disk. The arm 3 is pivoted by means of a horizontal shaft 12 on a bracket 13 which is solid with a vertical shank 14, rotating freely in a socket 15.

This device is intended to be used in the

case when the recording is made by oscillations parallel to the plane of the disk. A characteristic feature of the invention is to reproduce the movements taking place in a single direction.

We claim:

1. In a phonograph, a stylus-carrying arm for coaction with a disk, a magnetic blade having an extremity secured to said arm, a permanent magnet secured to the free end of the said blade and arranged with its poles in juxtaposition with said blade, and a spool having a hollow hub in which said blade oscillates transversely and thereby creates an electromotive force to transmit to a distance the sounds registered by the disk.
2. In combination with the style carrying arm of a talking machine, a magnetizable blade having one end secured on said arm, a permanent magnet secured on the free end of said blade and arranged with its poles opposed to opposite sides of said blade, a non-magnetic frame connecting the arms of

the magnet, and a coil secured to said frame and having a hollow core extending therethrough from end to end and through which hollow core said blade extends.

3. In combination with the style carrying arm of a talking machine, a magnetizable blade having one end secured on said arm, a permanent magnet secured on the free end of said blade and arranged with its poles opposed to opposite sides of said blade, a non-magnetic frame connecting the arms of the magnet, a coil secured to said frame and having a hollow core extending therethrough from end to end and through which hollow core said blade extends, and means to adjust said magnet with respect to the blade to arrange the poles of said magnet equidistant from said blade.

In testimony whereof we affix our signatures.

HENRI ARMAGNAT.
PIERRE FRELY.
